Primary Examiner—Alan P. Douglas*Assistant Examiner*—Antoine D. Davis*Attorney, Agent, or Firm*—Burns, Doane, Swecker & Mathis**[57] CLAIM**

The ornamental design for a cutting insert, as shown and described.

DESCRIPTION

FIG. 1 is a top, front perspective view of a cutting insert showing our new design;

FIG. 2 is a top, back perspective view thereof;

FIG. 3 is a front elevational view thereof;

FIG. 4 is a bottom plan view thereof;

FIG. 5 is a right side elevational view thereof;

FIG. 6 is a top plan view thereof;

FIG. 7 is a back elevational view thereof; and,

FIG. 8 is a left side elevational view thereof.

The left side and other end of the cutting insert are not shown as they are mirror images identical with the illustrated views.
